UNITED STATES PATENT OFFICE.

JACKSON DE NEAL, OF TOLEDO, OHIO, ASSIGNOR TO ALBERT M. CHAPMAN
AND MORTIMER J. MANN, OF SAME PLACE.

GAS-GENERATOR.

SPECIFICATION forming part of Letters Patent No. 507,975, dated October 31, 1892.
Application filed September 21, 1891. Serial No. 406,283. (No model.)

To all whom it may concern:

Be it known that I, JACKSON DE NEAL, of Toledo, county of Lucas, and State of Ohio, have invented certain new and useful Improvements in Electro-Carbon Gas-Generators; and I do hereby declare that the following is a full, clear, and exact description of the invention, which will enable others skilled in the art to which it appertains to make and use the same, reference being had to the accompanying drawings, and to the figures of reference marked thereon, which form a part of this specification.

My invention relates to an electro carbon gas generator, and has for its object to vaporize a hydro-carbon liquid, and cause the same to pass through a mass of carbonaceous, vegetable, mineral, or other material heated to incandescence, whereby the vapor shall be raised to a temperature, to convert the same into a fixed gas, and be enriched at the same time by the gases evolved from the mass within the generator.

A further object is to utilize an electric current in the vaporization and manufacture of the gas either as an initial step, or as auxiliary to the incandescent mass, or as the only primary source of heat as the mass within the generator is maintained in an incandescent condition thereby.

The invention consists in the parts, and combination of parts, hereinafter described and pointed out in the claims.

In the drawings:—Figure 1 is a longitudinal vertical sectional elevation of a generator of a preferred construction for carrying out my invention. Fig. 2 is a central transverse vertical section of the same.

1 designates an incasing shell which may be composed of metal, firebrick, or any material of a nature to withstand heat. Shell 1 is preferably formed with a rectangular base 2, having one or more air conduits 3, (two being shown in the present instance) the openings 4 to the conduits being regulated or closed by means of dampers 4, one being shown as closed by the full lines Fig. 1, and the dotted lines as opened, there being an opening 5, formed in one end of the shell to allow of removal of the incomplete products of combustion, the opening being closed by a cap during the

operation of vaporization. Shell 1, is further provided with a series of perforations 5' adapted to allow escape of heat when opened, and by means of a series of movable outer 55 coverings 6 to be closed to retain the heat therein, coverings 6 being formed with perforations 7 which register with openings 5' when adjusted as shown at the right hand side in Fig. 1—or closed when adjusted as 60 shown at the left hand side in the same figure.

8 designates a generator supported centrally of casing 1 and having a tubular casing 9 extending through the casing 1 through which an oil supply pipe 10 passes and extends to the center of the generator or nearly to the center, and is connected at this point. Pipe 10 is in direct communication with the oil supply and is provided with a valve 11 to regulate or cut off the flow of oil to the generator.

Generator 8 is formed with a vertical chamber 12, extending through and some distance above shell 1, and is provided with a closed cover 13, hinged as at 14, and secured closed 75 by a transverse pin 15, there being a rod 16 of a feeder 17 journaled therein, the rod being adapted to be revolved by means of a hand wheel 18 secured upon the upper end thereof.

19 designates a centrally perforated sphere or ball, provided with a handle 20 by which to revolve the ball to cause the perforation to register with the opening of chamber 12, or cut off communication therewith.

At diametrically opposite sides of shell 1 are formed perforations 21 through which are passed tubes 22 of glass, mica, or other suitable insulating material, there being supplemental tubes 23 of non-conducting material 90 which incase the tubes 22 to further insulate the casing 1 from electrical conductivity.

24 designates carbon points, which are passed through the insulating tubes 22, and nearly meet at their points 25 in direct alignment with the end of oil delivery nozzle 26 of oil pipe 10 the carbon points being electrically engaged by wires 27 of positive and negative polarity.

28 designates a pipe in vertical alignment 100 with nozzle 26, coinciding with the carbon points at their inner ends, this being the cen-

tral point of heat, and consequently the receptive point of gases, evolved from the oil and material within the generator, and is designed to receive the gas therefrom and convey the same to a place of storage or combustion.

In operation the object being as stated, to convert the oil into a fixed gas by a disintegration of the same by heat and also to incorporate therewith the gases evolved from the material within the generator, cover 13 is raised and a combustible gas evolving material inserted within the chamber 12, which material may be charcoal, or the cheap com-
15 minuted product from siftings anthracite or bituminous coal, or as a mineral it may consist of an ordinary metal as iron ore, or I may introduce ordinary garbage as collected from kitchens and refuse of cities, which when in-
20 troduced is urged into the generator by screw 17, and when the generator is sufficiently full, the electric current is turned on, causing the carbon points to attain from 1,800° to 2,600° of heat, valve 11 is opened and the oil permitted
25 to flow through nozzle 26 into the radius of incandescent material within the generator and is immediately converted into a gas, and permeates the heated mass of material within the generator, causing the same to evolve all
30 combustible properties therefrom, which intermingle with the hydro-carbon vapor and combine in forming a gas, which is received into pipe 28, and conveyed thereby to a place of storage or combustion. During the pro-
35 cess of converting the oil into the gas, the mass within the generator may be heated sufficiently to cause an inherent heat of sufficient intensity to cause the oil to be converted into gas, as for instance if the generator is filled
40 with coal, and the incandescent mass, is performing the work of vaporizing the oil, and incorporating the combustible gases there-
45 with, the electrical current may be cut off, and the mass be allowed to convert the oil by its own heat, it being understood that the current is employed as soon as the heat decreases, or when a new supply of material is charged into the generator, the idea of the invention being to provide for a continuous
50 manufacture of gas, by reason of a constant flow of oil, and a replenishing of the material within the generator as needed. In introducing a new charge of material into the generator while in operation, handle 20 of the
55 sphere 19 is turned to close the conduit, rod 16 and feeder 17, are raised when cover 13 is opened, and the material is introduced. When cover 13 is closed and fastened, sphere 19 is revolved to open the conduit, and the material is forced into the generator by revolving feeder 17, until the generator is full and pref-

erably densely packed. An electric current is now caused to pass through the carbon points, heating the mass within a limited radius of the points to incandescence, when oil is admitted to the generator and is quickly converted into a gas and unites with the gases evolved from the incandescent mass, and is either stored in a gasometer, or used in immediate combustion.

The purpose of the dampers 4 of shell 1 are to admit air to the interior of the shell, and surrounding the generator, to prevent too great heat of the shell of the generator, dampers 6 being for the purpose of allowing escape 75 of heat or confining the same.

It will be understood from the foregoing description, that I am enabled by my process to evolve all the gaseous products of the oil and material introduced into the generator 80 and that a material of the most crude nature may be employed with profit to be heated to incandescence, to and only be inherent heat, but by evolving combustible vapor.

What I claim is—

1. In an apparatus of the class described, the combination with an outer casing having air conduits, and a perforated top, of a cover or damper plate arranged to cover the perforations in said cover, a retort located centrally within the outer casing, a hopper passing through the casing and leading into the retort at the top, the valve and feeder located near the upper end of the hopper, the oil supply pipe passing into the retort to the center 90 of the same, the carbon points passing also into the retort, the electrical connection for the carbon points, and a gas conductor pipe for carrying off the gas produced within the retort.

2. In an apparatus of the class described, the combination with an outer casing having air conduits and a perforated top, of a cover or damper plate arranged upon said top, a centrally located retort, a hopper leading into 105 said retort at the top of the same, an oil supply pipe passing into the center of the retort, the carbon points passing also into the retort, the electrical connections for the carbon points, the gas conductor pipe leading from 110 the retort to the outside of the casing, and a screw feeder located in the hopper for feeding a solid gas evolving substance to the retort.

In testimony that I claim the foregoing as 115 my own I hereby affix my signature in presence of two witnesses.

JACKSON DE NEAL.
